UNITED STATES PATENT OFFICE.

GEORGE S. TRUMBORE, OF PENNSBURG, PENNSYLVANIA.

SPIITTOON-LIFTER.

SPECIFICATION forming part of Letters Patent No. 443,706, dated December 30, 1890.

Application filed July 12, 1890. Serial No. 358,584. (No model.)

To all whom it may concern:

Be it known that I, GEORGE S. TRUMBORE, a citizen of the United States, residing at Pennsburg, in the county of Montgomery and State of Pennsylvania, have invented certain new and useful Improvements in Spittoon-Lifters; and I do hereby declare the following to be a full, clear, and exact description of the invention, which will enable others skilled in the art to which it appertains to make and use the same.

My invention relates to various new and useful improvements in spittoon-lifters, and is especially adapted for use in connection with those spittoons having removable covers.

The objects of my invention are to provide and produce a spittoon-lifter which will be cheap to manufacture and simple and effective in use.

For a better comprehension of my invention attention is invited to the accompanying drawings, forming a part of this specification, and in which—

Figure 1 is a perspective view of the invention, and Fig. 2 a sectional view of the same.

In each of the above views corresponding parts are designated by the same letters of reference.

A represents a vertical standard, preferably made cylindrical, of wood, although it will be evident that it may be made of metal. This standard is provided at its upper end with a handle B of a shape to be conveniently grasped by the hand, and it is provided at its lower end with an enlarged cylindrical head C. Both the handle B and the head C are made, preferably, integral with the standard A, although they may be made separate therefrom of some other material.

Extending out from the cylindrical head C are a number, preferably three, of horizontal radiating arms D D D. Each of these radiating arms D D D is slotted at its outer end, and within each slotted portion is pivoted a right-angled lever E. Each right-angled le-

ver E is provided with a bent-in foot F, which is adapted to grasp the foot of the spittoon. Sliding upon the standard A is a sleeve G, provided with a number of ears H at its lower portion, corresponding in number and location with the right-angled levers E E E. Connecting each ear H with the upper end of the lever directly beneath it is a short rod I. The upward movement of the sleeve G is limited by means of one or more studs J.

The operation of my improved device is substantially as follows: The device is carried by the handle B, so that the sleeve G may drop by its weight so as to separate the foot portions of the right-angled lever. The foot portions are now placed beneath the spittoon and the device is raised by the sleeve G. This will cause the foot portions of the right-angled levers to approach each other, so as to firmly engage beneath the spittoon, which is then carried by the sleeve G. When it is desired to release the spittoon, the sleeve G is allowed to drop by its weight, which will allow the foot portions of the right-angled levers to separate.

Although my improved device is especially adapted for use with spittoons having removable covers, yet it should be understood that it can be used with any variety of spittoons.

Having now described my invention, what I claim as new therein, and desire to secure by Letters Patent, is as follows:

As an improved article of manufacture, a spittoon-lifter consisting of a vertical standard, a number of fixed radial arms at the lower end thereof, a right-angled lever pivoted at the end of each radial arm and having a bent-in foot to engage with the outer periphery of the spittoon, and a sliding sleeve on said standard and connected with said right-angled levers.

GEORGE S. TRUMBORE.

In presence of—

EUGENE W. SCHOLL,
EMMA SCHOLL.
